US0D1066044S

(12) **United States Design Patent** (10) **Patent No.:** **US D1,066,044 S**
(45) **Date of Patent:** **** Mar. 11, 2025**

(54) **SPRAY CAP**

(71) Applicant: **The Procter & Gamble Company**,
Cincinnati, OH (US)

(72) Inventors: **Mei San Gigi Cho**, Singapore (SG);
Bing Leng, Singapore (SG); **Rileigh**
Nicole Smyth, Cincinnati, OH (US);
Carley Michelle Giles, Columbus, OH
(US); **Austin Tyler Scott**, Westerville,
OH (US)

(73) Assignee: **The Procter & Gamble Company**,
Cincinnati (OM)

(**) Term: **15 Years**

(21) Appl. No.: **29/887,640**

(22) Filed: **Mar. 23, 2023**

(30) **Foreign Application Priority Data**

Sep. 29, 2022 (WO) WIPO123226

(51) **LOC (15) Cl.** **09-07**

(52) **U.S. Cl.**

USPC **D9/448**; D9/685

(57) **CLAIM**

The ornamental design for a spray cap as shown and described.

DESCRIPTION

FIG. 1 is a perspective view of a spray cap, embodying our new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines depict the environment of the spray cap and form no part of the claimed design.

1 Claim, 7 Drawing Sheets
